UNITED STATES PATENT OFFICE.

SYDNEY BUCKLEY, OF PHILADELPHIA, PENNSYLVANIA, ASSIGNOR TO NILES-BEMENT-POND COMPANY, OF NEW YORK, N. Y., A CORPORATION OF NEW JERSEY.

BRIDGE FOR TRAVELING CRANES.

1,296,757.

Specification of Letters Patent. Patented Mar. 11, 1919.

Application filed June 2, 1917, Serial No. 172,424. Renewed January 7, 1919. Serial No. 270,059.

To all whom it may concern:

Be it known that I, SYDNEY BUCKLEY, a citizen of the United States, and a resident of Philadelphia, in the county of Philadelphia and State of Pennsylvania, have invented certain new and useful improvements in Bridges for Traveling Cranes, of which the following is a specification, reference being had therein to the accompanying drawings.

The invention relates more particularly to traveling cranes of the class in which each comprises a movable bridge having two parallel separated elements respectively carrying rails. A hoisting mechanism is provided which consists of a trolley movable along the rails on the bridge and depending load engaging elements which usually extend between the two elements of the bridge. The invention relates especially to the bridge elements of cranes of the type specified, and a construction embodying my present invention is in some respects similar to the construction disclosed and claimed in my copending application for cranes, Serial No. 149,180, filed February 17, 1917. In the design of cranes, in order to meet the various and different requirements as concerns span, capacity, character of load, operating conditions, etc., it is necessary to vary the character of the bridge construction. The object of the present invention is to provide a bridge construction of the general type set forth in my aforesaid copending application but which is adapted to meet different requirements.

In the accompanying drawings I have illustrated the embodiment of the invention which I now deem preferable, but it will be understood that the construction shown is intended to be merely illustrative and is not intended to define or limit the scope of the invention. Particularly it will be understood that the forms of the girders, the shapes of the structural sections used, the means for connecting the several girders together and the various structural details can be varied widely in accordance with the requirements of any particular case or in accordance with the preferences of the designer.

Of the drawings:

Figure 1 is a side elevation of a crane embodying the invention, some of the parts to

which the invention does not directly relate being omitted.

Fig. 2 is a transverse vertical sectional view, the part at the left being taken along the line 2—2 of Fig. 3 and the part at the right being taken along the line 2A—2A of Fig. 3.

Fig. 3 is a longitudinal vertical sectional view taken along the center line 3—3 of one of the bridge elements.

Fig. 4 is a fragmentary plan view of one of the bridge elements, certain of the parts being broken away to show other parts.

Referring to the drawings, particularly to Figs. 1 and 2, it will be observed that I have shown a crane comprising a traveling bridge which is carried at its ends on trucks which travel along rails 1, 1 supported on suitable elevated structures 2, 2. The bridge is made up of two longitudinal elements arranged with a space between them. The two elements are connected at the ends by suitable transverse members 3 as shown in Fig. 2. Preferably there is provided a separate two wheeled truck element 4 for each end of each bridge element.

For the purpose of moving the crane as a whole along the rails 1, 1, one or more truck wheels at each end of the bridge are connected with a suitable driving motor. As illustrated, one of the truck wheels at each end is connected with a gear wheel 5 which meshes with a pinion 6 on a shaft 7 which extends longitudinally from one end of the bridge to the other. A motor 8 is provided for rotating the shaft 7, thus serving to move the bridge in one direction or the other as required.

Supported on each of the said longitudinal bridge elements is a rail 9. A suitable trolley or hoisting mechanism is provided which is supported on the rails 9, 9, and is adapted to travel along them. The hoisting mechanism as a whole is represented in the drawings by 10, but as this hoisting mechanism of itself constitutes no part of the present invention, detailed description thereof can be omitted. It is sufficient to point out that the hoisting mechanism is provided with a suitable load-engaging device such as the hook 11 which is suspended by a cable or cables 12, passing through the space between the two longitudinal elements of the bridge. By means of a motor 13 the rope can be

wound upon or unwound from a drum 14, thus causing the hook with its load to be raised or lowered.

There is a suitable cage 15 which is provided with space for an operator and with suitable controlling devices whereby the movements of the bridge and of the hoisting mechanism can be started, stopped and controlled as required.

10 The present invention relates primarily to the construction of the two main side elements of the bridge, and as these elements are similar to each other it will be sufficient to describe but one of them in detail. In 15 the drawings many of the structural details are omitted or are incompletely shown, as these constitute no part of the invention and can be varied as desired.

In the construction presented in my aforesaid application Serial No. 149,180, each side element of the bridge comprises two separated main girders and a supplemental rail-carrying girder located between the main girders. In the said construction the load is 25 transmitted to the ends of the bridge solely by the main side girders, the central rail-carrying girder merely serving to support the rail and to transmit the load from one panel point to the next, the load being transferred at the panel points to the main girders. The present construction differs from the aforesaid construction primarily in the provision of three main load-carrying girders which are equally or at least commensurate in carrying capacity. The rail is carried by the central one of these three girders and suitable cross connections are provided at intervals whereby the load is distributed to all three of the girders. As illustrated, 30 the three girders are substantially the same in size and construction, but it will be understood that a certain degree of variation may be had without departing from the spirit of the invention.

40 Each side element of the bridge has two side girders 16 and 17, and I prefer under most circumstances to construct these girders with upper and lower longitudinal compression and tension members and suitable 45 diagonal and upright connecting members. As shown, each girder has an upper compression member consisting of two channel beams 18 placed back to back and a lower tension member consisting of two channel 50 beams 19 placed back to back. Positioned 55 between the two pairs of channel beams of the said upper and lower members and extending diagonally, are truss members 20 and 21 which preferably are smaller channel 60 beams suitably connected to the channel beams 18 and 19 by gusset plates and rivets. At the ends of the bridge the upper and lower compression members of the girders are connected to suitable end structures 65 22, 22.

Positioned between the two side girders 16 and 17 is a central girder 23 which is preferably similar to the side girders 16 and 17. As shown, it comprises an upper compression member consisting of channel beams 24 placed back to back and a lower tension member consisting of channel beams 25 placed back to back. Positioned between the two pairs of channel beams 24 and 25 of the said upper and lower members and extending diagonally, are truss members 26 and 27 which preferably are smaller channel beams suitably connected to the channel beams 24 and 25 by gusset plates and rivets. At the ends of the bridge the upper and lower compression members of the central girder are connected to the aforesaid end structures 22, 22. Preferably at each point where two diagonal members 26 and 27 join the lower compression member there is provided an upright 28 which at its upper end is connected to the upper compression member.

Suitable transverse members are provided for connecting together all three of the girders. Preferably, in order that these transverse members may be suitably connected with the side girders and may suitably engage the central girder without any break therein, the central girder is positioned a little higher than the side girders. As illustrated, transverse connecting members are provided both at the top and at the bottom. The upper connecting members comprise two channel beams 29, 29 placed back to back and the lower transverse members comprise channel beams 30, 30 placed back to back. These channel beams 29 and 30 are suitably connected at their ends to the corresponding beams of the side girders and at their centers are connected to the under sides of the beams 24 and 25 of the central girder. The lower connecting members are provided at each point where the two diagonal members join the lower members, and the upper connecting members are provided at each point where two diagonal members join the upper member. For stiffening the structure, transverse diagonal braces 31 and 32 may be provided and also horizontal diagonal braces 33 and 34 at the top and 35 and 36 at the bottom. The details of these braces need not be described as they are well known to designers of structural steel constructions.

The rail 9 is carried by the upper compression member of the central girder 23. This member must be of sufficient strength to act as a beam and support the load from one set of connecting members 29, 29 to the next vertical member 28. Preferably, as shown, the upper member is on this account reinforced by a top plate 37 and a bottom plate 38.

It will be perceived from a consideration of the construction illustrated that substantially all of the metal is active for carrying the main load and for transmitting it to the

ends of the bridge. Practically the only metal (outside of the small diagonal braces) which is inactive for this purpose is that in the transverse connecting members 29 and 30. These connecting members, however, can be relatively light as they do not have to carry the whole load as do the corresponding members in the construction shown in my aforesaid copending application.

10 What I claim is:

1. The combination in a bridge for a traveling crane of six individually complete main girders extending from end to end, the girders being arranged in groups of three 15 with those in each group equally spaced, two rails supported respectively on the central girders of the groups, and connecting members for transmitting parts of the rail loads from the central girders to the adjacent side 20 girders.

2. A traveling crane bridge element consisting of three equally spaced individually complete main girders extending from end to end, a rail supported on the central girder, 25 and connecting members for transmitting parts of the rail load from the central girder to the side girders.

3. A traveling crane bridge element consisting of three equally spaced individually 30 complete main girders extending from end to end, each girder comprising an upper longitudinal compression member, a lower longitudinal tension member and diagonal truss members, a rail supported on the upper member 35 of the central girder, and connecting members for transmitting parts of the rail

load from the central girder to the side girders.

4. A traveling crane bridge element consisting of three similar equally spaced individually complete main girders extending from end to end, each girder comprising an upper longitudinal compression member, a lower longitudinal tension member and diagonal truss members, a rail supported on 40 the upper member of the central girder, and transverse members connecting the three girders at each point where diagonal members join the vertical members and serving to distribute the rail load. 45

5. A traveling crane bridge element consisting of three similar individually complete main girders extending from end to end and each comprising an upper longitudinal compression member, a lower longitudinal tension member and diagonal truss members, the three girders being equally spaced horizontally and the central girder being at a higher elevation than the side girders, a rail supported on the upper members of the 50 central girder, and transverse load-carrying members connecting all three girders at each point where diagonal members join the vertical members, the said transverse members being joined horizontally to the longitudinal 55 members of the side girders and engaging the bottoms of the longitudinal members of the central girder.

In testimony whereof, I hereto affix my signature.

SYDNEY BUCKLEY.
